ABSTRACT OF THE DISCLOSURE

A generally cylindrical metal rung which has four diametrically opposite longitudinal ribs; two of the ribs defining the top of the rung and are bent outwardly away from one another. The space between the top ribs is the step and has a plurality of longitudinal grooves and at least a middle portion is serrated and dented in such fashion as to lock the material which forms the frictional step surface on the rung; this frictional step surface is formed as follows: epoxy is applied to the serrated middle portion of the top of the rung so as to substantially fill the space between the top ribs, then a layer of grit is placed upon and pressed into the epoxy and baked, and while still hot another layer of epoxy is spread on the grip surface so as to solidify and integrate the friction layer on the rung; the extreme ends of the rung are provided with spaced teeth and pressed into a hole in the respective rails of the ladder, the hole containing epoxy so that the epoxy flows around the toothed end portion of the rung and also into the end of the rung to cushion and bind the rung in place.

BRIEF DESCRIPTION OF THE INVENTION

The invention is to obviate the peeling off of the friction surface from the top of such rung and also eliminates the disadvantage of the grip surface projecting to the exposed edges of the rung and catching the trousers or scratching the legs of the user; such disadvantages are eliminated by the method steps whereby the epoxy and the grit are integrated into the serrations on the step portion of the rung; and confined between the top ribs which present protective rounded edges for contact, the rung being held from turning or becoming loose by a plurality of teeth on its end so directed as to bite into the walls of the hole in the respective rails of the ladder and by the provision of the binding and cushioning packing of epoxy in said holes of the rails.

DESCRIPTION OF FIGURES.

FIG. 1 is a fragmental plan view of the rung.

FIG. 2 is a fragmental sectional view of the rung in the ladder.

FIG. 3 is a side view of rungs in an extension ladder hooked for extended position.

FIG. 4 is a cross-sectional view of a rung before the friction filler is applied.

FIG. 5 is a sectional view of the rung with friction filler.

DETAILED DESCRIPTION

The rung is made of a cylindrical tubular body 1, the ends 2 of which fit into holes 3 in the opposite rails of a latter.

There are four diametrically opposite longitudinal ribs projecting from the outer periphery of the body 1, which are so located that a pair of flange ribs 6 project outwardly and define the top or step surface of the rung and another pair of ribs 7 project downwardly and somewhat outwardly from the periphery of the body 1. These ribs 6 and 7 form abutments when the ladder is manipulated

2

at any incline, so that lateral impact or stress is exerted on the ribs which reinforce the rung body 1.

A friction surface is produced in the space 8 between the top flange ribs 6 by the following steps: the surface of the body between the flange ribs 6 is grooved longitudinally and somewhat flattened and indented transversely to form locking pockets 9 generally in the manner of serrations; a binder, such as epoxy, is spread between the flange ribs 6 filling the space 8 to about the edges of the flange ribs 6; suitable grit is spread on the epoxy so as to penetrate into the epoxy, and the filler is baked to a suitable hard consistency; then while the filler is still hot another layer of epoxy is spread over the grit so as to set and harden and form the step surface on the rung.

The edges 11 of the flange ribs 6 are rounded and protect the user from abrasion by the grit, and also protect the friction layer from transverse or lateral shearing forces thereby further to prevent the loosening or peeling of the friction surface.

Spaced from but near each end of the rung body 1 each flange rib 6 is dented to form a socket 12. When the rung is used in an extension ladder, as shown in FIG. 3, hooks 13 are used to hold the ladder extended, and the sockets 12 are located near the adjacent rails 4 to nest the respective hooks 13.

On each end 2 of the rung body 1 is provided a plurality of annular series of teeth 14 the sharp outer ends 16 of which incline toward the opposite end so as to bite into the walls of the holes 3 and further resist pulling out of the hole 3.

An annular groove 17 is formed in the bottom 18 of each hole 3 conforming to the extreme end of the tubular body 1. Epoxy placed into the hole 3 flows around the outer periphery of the end 2 and is also trapped into a plug 19 on the bottom 18 of the hole 3 so as to bind and cushion both the inside and outside of the tubular end 2.

The method and rung herein obviates the tearing off or peeling the friction surface from the top of the rung, it protects the user, it also protects the step surface, prevents loosening of the rung, and generally prolongs the utility of the ladder.

I claim:

1. A rung for securing in the rails of ladders comprising

- (a) a generally cylindrical body,
- (b) at least a pair of parallel longitudinal ribs spaced apart to define a step surface on the top of the body,
- (c) friction means confined between said ribs and substantially filling said space and being bound to said body and to said ribs, whereby said ribs protect the respective edges of said friction means,
- (d) said rails having holes for the ends of said rungs,
- (e) said body being tubular metal,
- (f) a plurality of annular series of teeth projecting from the periphery of each end of said body and being fitted into said holes in the respective rails and being adapted to bite into the walls of the respective holes,
- (g) each of said holes having an annular pocket to receive the extreme end of said tubular body and containing a binder to form cushioning securing means around said teeth and inside the end of said body.

2. A rung for securing in the rails of ladders comprising

- (a) a generally cylindrical body,
- (b) at least a pair of parallel longitudinal ribs spaced apart to define a step surface on the top of the body,
- (c) friction means confined between said ribs and sub-

- stantially filling said space and being bound to said body and to said ribs, whereby said ribs protect the respective edges of said friction means,
- (d) said ribs projecting respectively outwardly from said body thereby to form abutments on said rung, 5
- (e) said ladder being an extension ladder and having locking hooks,
- (f) said ribs being dented spaced from but near each end thereby to form sockets adjacent each rail for 10 engagement with said locking hooks.
